[57] CLAIM

The ornamental design for a bypass valve for a liquid treatment tank, as shown and described.

DESCRIPTION

FIG. 1 is a front perspective view of a bypass valve for a liquid treatment tank showing our new design;

FIG. 2 is a top plan view thereof;

FIG. 3 is a left side elevational view thereof;

FIG. 4 is a rear elevational view thereof;

FIG. 5 is front elevational view thereof;

FIG. 6 is a right side elevational view thereof;

FIG. 7 is a bottom plan view thereof; and,

FIG. 8 is an exploded front perspective view thereof.
